UNITED STATES PATENT OFFICE.

ALBERT PETIT, OF LOS ANGELES, CALIFORNIA.

SAFETY-STOP FOR ELEVATORS.

1,158,150.

Specification of Letters Patent. Patented Oct. 26, 1915.

Application filed March 27, 1915. Serial No. 17,379.

To all whom it may concern:

Be it known that I, ALBERT PETIT, a citizen of the United States, residing at Los Angeles, in the county of Los Angeles, State 5 of California, have invented new and useful Improvements in Safety-Stops for Elevators, of which the following is a specification.

This invention relates to safety stops for 10 elevators and the like; and the object of this invention is the provision of simple, efficient and trustworthy means for effectively stopping an elevator when its speed has increased to a dangerous point.

15 The mechanical features may be best understood by reference to the accompanying drawings, wherein I have shown a specific form of my invention, and to the following specification wherein said specific form is 20 described and the operation and utilities of my invention are set forth.

For the purpose of this specification I illustrate a preferred specific form of my invention in the accompanying drawings, in 25 which—

Figure 1 is a vertical side elevation of an elevator equipped with my improved stop mechanism, Fig. 2 is a front elevation of the same, Fig. 3 is a detail section taken as indicated by line 3—3 of Fig. 1, and Fig. 4 is a section taken as indicated by line 4—4 of Fig. 1.

In the drawings the numeral 10 may designate the body of a car or cage of the elevator and 11 the way or ways upon which the cage is adapted to move. Any suitable means may be used for engaging the cage with the ways, as is illustrated at 12.

My improved stop mechanism includes the 40 combination of a gripping device and a means for normally holding the gripping device in inoperative position, a means, such as a spring means for throwing the gripping device to operative position, and a 45 means which is controlled or actuated by the speed of the cage for releasing the holding means which hold the gripping device out of action. The specific details of a preferred form of this mechanism are explained 50 as follows: I provide a horizontally movable pivot 13 upon the cage 10, said pivot 13 being mounted in a small frame 14 which is pivotally mounted at 15 to the cage itself. A way gripping bar 16 is mounted on the 55 pivot 13 and this bar has in its outer end a notch 17 adapted to normally loosely en-

gage around the way 11 when the bar 16 is in its normal substantially horizontal position. There are two of these bars 16, one on each side of the cage, each engaging one 60 of the opposite ways 11. I utilize vertically sliding bars 18 which carry rollers 19 above and below the bar 16, so that vertical movement of the bars 18 will cause movement of the bars 16 around their pivots 13. 65 The two vertical sliding bars 18 are joined to a horizontal cross member 20 at their lower ends; and springs 21 are adapted to press the cross member 20 and the bars 18 downwardly. The springs 21 are merely 70 used for the purpose of quickening the action in pressing the cross member 20 and the bars 18 downwardly; the action of these members would be the same without the springs 21 but not so fast and sure. The 75 bars and the cross member are normally held from downward movement by the action of the spring pressed pawl 25 which enters under a roller 26 mounted in the cross member 20. This pawl 25 is mounted in a suitable bearing or hanger 27, the spring 28 pressing it outwardly into position beneath the roller 26. A hand lever 29 connected by rod 30 with a lever 31 which is connected at 32 with the cross member 20, serves the purpose of raising the cross member and the bars 18 to their normal position. The pawl 25 is operated by the horizontal movement, 80 in either direction, of an arm 35, to which arm the pawl is pivotally connected at 36; 85 and the arm has a cam 37 on its end bearing against the hanger 27, the cam being of such shape that when the arm 35 is moved in either horizontal direction the pawl 25 is withdrawn from beneath the roller 26, allowing 90 the cross member to be moved downwardly.

It will be seen from the foregoing description that the mechanism so far described includes a means for gripping the way, and a means for normally holding said gripping means in its inoperative position, and means (the springs 21) for throwing the gripping means to operative positions when the holding means is released. The 105 mechanism for operating the holding means to release it is now explained. On the under side of the cage I mount a shaft 40 in bearings 41 which are supported on oscillating arms 42; and a spring 43 serves the purpose 110 of throwing the arms 42 in the direction shown; so that a friction wheel 44 which is

mounted upon the shaft 40 will be thrown against the way 11. This friction wheel preferably has a rubber or similar tire 45 so that a good frictional contact with the way 11 is assured. I also mount a large gear wheel 46 upon the shaft 40, meshing with a smaller wheel or pinion 47 upon a shaft 48 which is also mounted on oscillating arms 49. The oscillating arms 42 and 49 are connected together by connecting rod 50 in such manner that the two shafts 40 and 48 are kept at a constant distance from each other to keep the gears 46 and 47 in proper mesh. The gearing arrangement is such that the shaft 48 revolves at a considerable speed. Mounted upon this shaft 48 beneath the arm 35 which operates the pawl 25, I place a wheel or disk 55 carrying a plurality of outwardly movable weights 56. These weights are opposed in their outward movement by the springs 57; and the springs are of such strength that the weights will not move outwardly until a certain predetermined speed is attained. When the car exceeds this pre-

determined speed, then the weights 56 are thrown outwardly by centrifugal force and they strike the arm 35 and move it in one direction or the other, so as to retract the pawl 25 and allow the cross member 20 to be moved downwardly by the springs 21. This movement of the cross member and of the bars 18 connected thereto causes the bars 16 to move to a diagonal position so that the notches 17 will grip or bind on the ways 11; and the car is then held from further downward movement. Since movement of the arm 35 in either direction will cause retraction of the pawl 25, it will be seen that excessive speed of the car either upwardly or downwardly will cause retraction of the pawl and operation as described. The springs 57 may be arranged in strength so as to allow the outward movement of the weight 56 at any predetermined speed.

Having described a specific form of my invention, I claim:

1. In combination with a vertical way and an elevator cage movable thereon, a way gripping means on the cage embodying a

way gripping bar holding a notch adapted to loosely engage around the way when the bar is in substantially horizontal position, a horizontally movable pivot on the cage on which pivot the bar is mounted, means including a pawl for holding the arm normally in substantially horizontal position, spring means for throwing the arm to an inclined position, an arm connected with said pawl so that movement of the arm causes movement of the pawl to release the way gripping arm, and means to move said pawl arm including a wheel mounted on the cage and in peripheral frictional contact with the way, spring means for holding said wheel in contact with the way, another wheel geared to said first mentioned wheel, outwardly movable weights on said last mentioned wheel, and springs opposing the outward movement of the weights, the weights being thrown outwardly by centrifugal action to strike the pawl arm, substantially as described.

2. In combination with a vertical way

and an elevator cage movable thereon, a way gripping means, means for normally holding said way gripping means out of action, a frame pivotally mounted upon the car, a way engaging wheel mounted upon said frame, a spring exerting pressure upon said frame to press the wheel into peripheral contact with the way, another wheel mounted upon said pivoted frame in fixed relation to said first mentioned wheel, gearing connection between the two wheels, outwardly movable weights on the second mentioned wheel, springs opposing the outward movement of said weights, and a member connected to said grip holding means and positioned so as to be struck and moved by said outwardly movable weights on said second mentioned wheel.

In witness that I claim the foregoing I have hereunto subscribed my name this 19th day of March 1915.

ALBERT PETIT.
